Primary Examiner — T Chase Nelson*Assistant Examiner* — Jonathan J. Han(74) *Attorney, Agent, or Firm* — Quarles & Brady LLP**(57) CLAIM**

The ornamental design for a shoe, as shown and described.

DESCRIPTION

FIG. 1 is a left side perspective view of an ornamental design for a shoe;

FIG. 2 is a left side view of the shoe of FIG. 1;

FIG. 3 is another left side perspective view of the ornamental design with alternative environmental structure;

FIG. 4 is a left side view of the shoe of FIG. 3;

FIG. 5 is yet another left side perspective view of the ornamental design with alternative environmental structure; and,

FIG. 6 is a left side view of the shoe of FIG. 5.

The dash-dash-dash broken lines are included for the purpose of illustrating portions of the shoe that form no part of the claimed design.

1 Claim, 6 Drawing Sheets**Related U.S. Application Data**

application No. 29/682,372, filed on Mar. 5, 2019, now Pat. No. Des. 885,724, which is a division of application No. 29/621,562, filed on Oct. 10, 2017, now Pat. No. Des. 855,953.
